UNITED STATES PATENT OFFICE

172,012

FINGER RING SHANK

Emo D. Erlanger, Los Angeles, Calif.

Application April 7, 1953, Serial No. 24,395

Term of patent 14 years

(Cl. D45—10)

To all whom it may concern:

Be it known that I, Emo D. Erlanger, a citizen of the United States, residing at Los Angeles, county of Los Angeles and State of California, have invented a new, original, and ornamental Design for a Finger Ring Shank, of which the following is a specification, reference being had to the accompanying drawing, forming a part thereof.

Fig. 1 is a perspective view of a finger ring shank, showing my new design;

Fig. 2 is a front elevational view thereof; and
Fig. 3 is a side elevational view thereof taken

in the direction indicated by the arrows along the line 3—3 of Fig. 2.

I claim:

The ornamental design for a finger ring shank, as shown.
